(57) **CLAIM**

I claim the ornamental design for a filter member for discriminating cells, as shown and described.

DESCRIPTION

FIG. 1 is a front and top perspective view of a filter member for discriminating cells of the present invention;

FIG. 2 is a front and bottom perspective view thereof;

FIG. 3 is a rear view thereof;

FIG. 4 is a front view thereof;

FIG. 5 is a first side view thereof;

FIG. 6 is a second side view thereof;

FIG. 7 is a top view thereof;

FIG. 8 is a bottom view thereof; and,

FIG. 9 is a front and top perspective view thereof shown in a different environment.

The broken lines shown represent unclaimed subject matter and form no part of the claimed design.
